UNITED STATES PATENT OFFICE

WILLIAM H. KAY AND ESKEL McDANIEL, OF ST. LOUIS, MISSOURI

HEADLIGHT

Application filed March 7, 1932. Serial No. 597,298.

This invention relates to certain new and useful improvements in headlights, the peculiarities of which will be hereinafter fully described and claimed.

5 The main objects of our invention are to provide means first, for avoiding the glare often thrown into the eyes of an adjacently passing motorist; second, for increasing the light given out by the reflecting means located above the horizontal plane through the lamp; third, for producing horizontal direct rays and downward secondary rays from the same reflector; fourth, for focusing said secondary downward rays towards the 10 changing foreground ahead of the headlight while projecting direct rays from a main reflector in parallel lines to the limit of their projection; fifth, for variably reflecting direct rays upward to the upper reflector from 15 which they are reflected as secondary rays, and varying the point in the foreground where they focus; and sixth, for normally hiding the lamp from direct front view of an approaching motorist.

20 In the accompanying drawing in which like reference numerals indicate corresponding parts,

Fig. 1 represents a front view of a headlight exemplifying our invention;

25 Fig. 2, a plan view of the same;

Fig. 3, an enlarged central vertical section on the line 3—3 of Fig. 2; and

30 Fig. 4, a separate plan view of our grid reflector in its preferred form as made in sheet metal.

Referring to the drawing, the numeral 3 designates a flat light transmitting plate in the front end of a casing having a curved top 4 and vertical sides 5 below a horizontal 35 axis X which are connected by a flat, substantially trapezoidal bottom 6, adapted to enclose the upper half of a parabolic or other suitable reflector 7, mounted on a substantially horizontal axis X. An electric or other suitable lamp 8, is operatively mounted in the focal point of said reflector, so that direct rays from the lamp are reflected forward in preferred substantially horizontal parallel lines A as indicated in Fig. 3, for 45 distance projection.

A horizontally disposed auxiliary reflector of substantially trapezoidal shape corresponding to said bottom is mounted within the casing, and consists of transverse slats 9 forming multifaced reflecting surfaces separated by open spaces 10 and fastened at fixed inclinations between vertical side bars 11 converging towards the rear, where they are preferably hinged on a horizontal rod 12 to allow of adjusting said auxiliary reflector as indicated, such as by means of a threaded vertical link 13, pivoted to said auxiliary reflector and passing down through said bottom. The lower end of said link has a knurled nut 14 and jam nut 15 disposed respectively above and below a bracket 16 on said bottom.

Said slats have a reflecting upper surface and are arranged in steps that rise successively higher toward the front, so that direct 40 forward rays from the lamp will pass to all of said slats, as indicated. The side bars are correspondingly curved upward toward the front, and the slats are inclined rearwardly downward, preferably at lessening inclination to the horizontal axial plane, so as to reflect said rays upward to meet the upper reflector, from which they are secondarily reflected forward.

The preferred adjusted position of the auxiliary reflector, as shown in Fig. 3, causes these secondary rays B to be projected convergingly downward as indicated, so as to focus at or near the ground for lighting the changing foreground, while the parallel rays A from the upper reflector light the distance to the limit of their projection.

The rear end 17 of the auxiliary reflector is preferably formed semicylindrical, with a concave reflecting surface below the lamp as a center, so that downward rays from the lamp are reflected upward with other upward rays from the lamp, and increase the brightness of the rear end of the upper reflector.

The said open spaces 10 obviate any chance of accidental rays or diffused light being reflected upward outside the headlight into the eyes of an adjacently passing motorist.

We do not limit our invention to the con-

struction shown, except by the appended claims.

We claim:

- 5 1. A headlight comprising the upper half of a parabolic reflector, a lamp mounted therein, a casing having a curved top and vertical sides below the horizontal axis which are connected by a substantially trapezoidal bottom, an auxiliary multifaced reflector of substantially trapezoidal shape 10 corresponding to said bottom and hinged at its straight rear edge for adjustment between said straight sides of the casing, and adjusting means therefor, substantially as 15 described.
- 20 2. In a headlight, the combination with a main reflector and its lamp, of a casing having a substantially trapezoidal bottom connecting vertical sides, an auxiliary reflector of corresponding trapezoidal shape having integrally formed transverse reflecting slats and vertical sides and hinged by its straight rear edge at the rear of said casing, and 25 means to adjust the auxiliary reflector, substantially as described.

In testimony whereof, we have affixed our signatures.

WILLIAM H. KAY.
ESKEL McDANIEL.
